YARN PACKAGE SUPPORT

William T. Stearn, Cumberland, Md., assignor to
Celanese Corporation of America, New York,
N. Y., a corporation of Delaware

Application October 18, 1950, Serial No. 190,818

8 Claims. (Cl. 242—122)

1

This invention relates to yarn package supports and relates more particularly to cone tubes. One type of yarn package that is widely employed in the textile industry is the cone which comprises a tapered tubular support or cone tube of paper or like material having yarn windings positioned thereon in such a manner that the ends of the support project from the yarn wound thereon. During the handling of the cones, it is customary to lift the cones by inserting a finger into the upper or smaller end of the cone tube thereby to avoid all contact with and possible damage to the yarn windings thereon. In unwinding yarn from the cones, the yarn is drawn axially over the smaller end thereof, which end must be smooth to avoid snagging and abrading or even breaking the yarn during the unwinding operation. One method widely employed for smoothing the end of the cone tube is to curl the material of the cone tube inwardly forming a smooth, rounded lip that projects toward the axis of the cone tube and over which the yarn may pass without damage. While the provision of a lip of this type avoids damage to the yarn, it reduces the size of the opening of the smaller end of the cone tube, making it difficult to insert a finger into said cone tube during the handling thereof.

It is an important object of this invention to provide a cone tube which will be free from the foregoing and other disadvantages.

A further object of this invention is to provide a cone tube having a smooth end over which the yarn may pass without damage and having an opening of sufficient size to permit a finger to be inserted therein readily.

Another object of this invention is to provide a cone tube having a rigid end that will be highly resistant to crushing.

Other objects of this invention will be apparent from the following detailed description and claims.

According to the present invention, there is provided a cone tube formed from a tapered tubular blank of paper or the like. At its smaller end, the thickness of the wall of the blank is reduced in such manner as to form a ledge extending around the entire inner circumference of the blank. The end portion of the blank is then folded inwardly until the tip thereof abuts said ledge and until the adjacent faces of the folded portion contact one another. By reducing the thickness of the end portion of the wall of the blank approximately one-half, it is possible to form a cone tube having a wall of substantially uniform thickness throughout its length.

A preferred embodiment of this invention is shown in the accompanying drawing, wherein

Fig. 1 is a cross-sectional view of the cone showing the yarn winding in broken lines, and

2

Fig. 2 is a cross-sectional view of the upper end of a blank from which the cone tube shown in Fig. 1 is formed.

Referring now to the drawing, the reference numeral 11 designates generally a cone, comprising a tapered, tubular cone tube 12 having positioned thereon yarn windings 13. The cone tube 12 is formed from a tapered tubular blank 14 comprising four plies 15 of paper. At its smaller end 16, the two inner plies 15 of the blank 14 are somewhat shorter than the two outer plies of said blank and form a ledge 17 extending around the entire inner circumference of the blank. To form the cone tube 12, the two outer plies 15 of the blank 14 are folded inwardly until the lip of said outer plies abuts the ledge 17 and the adjacent faces of said outer plies are in contact with one another as shown in Fig. 1 of the drawings.

Advantageously, the two outer plies 15 of the blank 14 form approximately one-half the total thickness of the walls of said blank so that after the outer plies at the upper end portion of the blank are folded the walls of the cone tube 12 will be substantially uniform in thickness throughout their entire length. In this way, there is obtained a cone tube having a smooth end over which yarn may pass without damage and having an opening at its smaller end sufficiently large to permit a finger to be inserted therein readily during the handling thereof. In addition, because of the abutment of the tip of the outer plies 15 against the ledge 17, the nose of the cone tube is extremely rigid and highly resistant to crushing.

It is to be understood that the foregoing detailed description is given merely by way of illustration and that many variations may be made therein without departing from the spirit of my invention.

Having described my invention, what I desire to secure by Letters Patent is:

1. A yarn package support comprising a tubular member for supporting yarn windings thereon, said tubular member having an end portion comprising an extension of said tubular member having a thickness less than the thickness of the main body of said tubular member, said extension being bent upon itself.

2. A yarn package support comprising a tubular member for supporting yarn windings thereon, said tubular member having an end portion comprising an extension of said tubular member having a thickness less than the thickness of the main body of said tubular member, said extension being bent upon itself, the resulting thickness of said end portion being substantially the same as that of the main body of said tubular member.

3. A yarn package support comprising a tubular member for supporting yarn windings thereon, said tubular member being formed of a plurality of plies, the outer plies being longer than the inner plies and forming an end portion having a thickness less than the thickness of the main body of said tubular member, said end portion being bent upon itself.

4. A yarn package support comprising a tubular member for supporting yarn windings thereon, said tubular member being formed of a plurality of plies, the outer plies being longer than the inner plies and forming an end portion having a thickness less than the thickness of the main body of said tubular member, said end portion being bent upon itself, the resulting thickness of said end portion being substantially the same as that of the main body of said tubular member.

5. A yarn package support comprising a tubular member for supporting yarn windings thereon, said tubular member being formed of a plurality of plies, the outer plies being longer than the inner plies and forming an end portion having a thickness less than the thickness of the main body of said tubular member and the tops of the inner plies forming a circumferential ledge, said end portion being bent upon itself so that the tip thereof abuts said ledge.

6. A yarn package support comprising a tubular member for supporting yarn windings thereon, said tubular member being formed of a plurality of plies, the outer plies being longer than the inner plies and forming an end portion having a thickness less than the thickness of the main body of said tubular member and the tops of the inner plies forming a circumferential ledge, said end portion being bent upon itself so that the tip thereof abuts said ledge,

5

the resulting thickness of said end portion being substantially the same as that of the main body of said tubular member.

7. A cone tube comprising a tapered tubular member formed of a plurality of paper plies for supporting yarn windings thereon, the outer plies being longer than the inner plies, being substantially one-half the thickness of the main body of said tubular member, and forming an end portion, said end portion being bent upon itself, the resulting thickness of said end portion being substantially the same as that of the main body of said tubular member.

10 8. A cone tube comprising a tapered tubular member formed of a plurality of paper plies for supporting yarn windings thereon, the outer plies being longer than the inner plies, being substantially one-half the thickness of the main body of said tubular member, and forming an end portion, and the tops of the inner plies forming a circumferential ledge, said end portion being bent upon itself so that the tip thereof abuts said ledge, the resulting thickness of said end portion being substantially the same as that of the main body of said tubular member.
